Francis M. Hess,

UNITED STATES PATENT OFFICE.

FRANCIS M. HESS, OF WHITING, INDIANA.

STILL FOR HYDROCARBON DISTILLATION.

Application filed November 20, 1922. Serial No. 601,971.

To all whom it may concern:

Be it known that I, FRANCIS M. HESS, a citizen of the United States, residing at Whiting, in the county of Lake and State of 5 Indiana, have invented certain new and useful Improvements in Stills for Hydrocarbon Distillation, of which the following is a specification.

This invention relates to boilers or stills 10 such as are employed for hydrocarbon distillation purposes, and is mainly, although not exclusively, intended for use in distillation apparatus wherein the material to be distilled is cracked under pressure in the 15 presence of a catalytic or contact body.

Petroleum oils to be cracked under pressure crack much more easily in the presence of some metals and compounds; such, for examples, as iron shavings, powdered copper, 20 silver, nickel, cobalt and fuller's earth. The main purpose of my present invention is to provide a still or boiler of such a structure as to cause the material heated and vaporized therein to flow therethrough in contact 25 with the catalyzing agent, the latter being in a finely divided condition so as to afford intimate contact thereof with the flowing stream of oil.

My invention is preferably, and as herein 30 shown and described, embodied in a still possessing the general structural characteristics of the still or vapor box forming the subject matter of Letters Patent No. 1,443,743 granted to me on the 30th day of January, 35 1923, and consisting generally of two series of internested broad flat heating plates forming between them a zigzag conduit through which the material flows in a broad thin stream while being heated; but, in the 40 broader aspects of the invention, it is not limited to stills of this particular type.

In order that the invention may be made intelligible to persons skilled in the art to such an extent as will enable the latter to 45 practice the same, I have, in the accompanying drawing, illustrated one practical and efficient embodiment thereof; and referring thereto—

Fig. 1 is a vertical sectional elevation of a 50 still or boiler embodying my improvements;

Fig. 2 is an enlarged cross-section through a pair of heating plates, on the line 2—2 of Fig. 1; and

Fig. 3 is a perspective elevation of one of 55 the mats or holders for the catalyzing agent

which is superimposed on the upper heating plate of each pair in the path of flow of the oil thereover.

Referring to the drawing, and first describing an improved form of vapor box or still designed for use in cracking systems such as I have disclosed in a former application, Serial No. 566,470, filed on the 7th day of June 1922, R designates a residuum tank mounted on a suitable foundation and capable of sustaining the maximum internal pressures employed in cracking systems of distillation. On this tank is mounted the boiler or still having a specific structure as follows. 10 designates the lower head of a 60 cylindrical metal tank constituting the housing or shell of the vapor generator. This tank head 10, as herein shown, is mounted and supported directly on a residuum tank R by suitable legs 11, and communicates with 65 said tank by a central tube 12 through which the residuum flows from the bottom of the still directly into the residuum tank. Mounted on the tank head 10 are two pairs of parallel upright frame structures designated as 70 75 an entirety by 13, which constitutes supports for a pair of generally W-shaped groups (left and right) of hollow heating plates joined at their convergent ends by hollow 80 headers internested so as to form between 85 adjacent plates of the two groups a continuous zigzag conduit for the gravity flow of the crude material in a broad thin continuous film or stream from top to bottom. The 90 heating plates of both groups are structurally identical and are best illustrated as to details in the sectional view, Fig. 2, wherein 14 designates a group of tubes disposed side by side at equally spaced intervals, and 15 designates each of a pair of longitudinally 95 corrugated boiler plates which overlie and underlie respectively the tubes 14, and 16 designates rivets uniting the two plates midway between adjacent tubes 14. This forms 100 a hollow heating plate structure which provides two separate groups of conduits for heating media, namely, the interiors of the tubes 14, and the passages formed between adjacent tubes 14 and the plate sections spanning adjacent tubes. The inner 105 convergent ends of each connected pair of heating plates are united, so as to render the internal conduits of said plates continuous, by a hollow head or manifold 17 that extends 110 transversely of the ends of the heating plates

and is provided with a central longitudinal partition or bridge plate 18 extending from end to end thereof, the tubes 14 extending through the partition or bridge plate and thus communicating with each other through the chamber of the header on the outer side of said partition, and the ducts between the tubes communicating with each other through the chamber on the inner side of said partition. The outer ends of the convergent heating plates are united by spaced headers 17, the outer and inner chambers of which communicate with each other through pipes 19 and 20. Each header is provided at its ends with trunnions by which it is supported in the frames 13.

The above described structure affords a continuous zigzag multiple tube conduit for upward flow of a heating agent through the heating plate tubes 14, the outer header chambers, and the pipes 19, and another continuous multiple tube zigzag conduit for the upward flow of another heating medium through the passages formed by and between the tubes and the boiler plates, the inner chambers of the headers, and the pipes 20. In the arrangement shown the last mentioned multiple tube conduits are used for the upward flow of the primary heating medium, preferably superheated steam, while the first mentioned group of conduits is employed for the upward flow of residuum from the residuum tank R; the superheated steam being admitted through a pipe 21 and branch pipes 22 and 23, and the residuum from the tank R being forced upwardly, under the internal pressure, through the supply pipes 24. To insure the downward and forward flow of the material in process, the longitudinal edges of each plate which forms a part of the trackway or path of the material are turned upwardly, as best shown at 15' in Fig. 2, to a level slightly above the height of the headers, thus preventing lateral spilling or overflow of the material in process, and insuring its continuous downward flow in a zigzag direction over the header at the foot of the plate down onto the next underlying heating plate.

Surrounding and completely enclosing the vapor generating apparatus above described is a cylindrical tank or bell, comprising a tank body 25 and an upper tank head 26 which may be integral or continuous with the body 25, and is so shown herein. The lower tank head 10 and the tank body 25 have mating flanges 10' and 25' formed to provide a tongue and groove joint and united by bolts or rivets 27. The still housing or tank is, of course, constructed of a material capable of withstanding the maximum internal pressure under which the system may be operated.

From the inner chambers of the topmost headers of the two series of heating plates

branch pipes 28 and 29 and a main pipe 30 connected thereto conduct off the steam; and similar branch pipes 31 and 32 and a main pipe 33, connected into the outer chambers of the topmost headers of the two series 70 serve to conduct off the residuum.

The vapor is conducted off from the top of the tank through a pipe 34, union 35 and pipe 36, and the material in process is supplied to the still by the same conduit; the 75 material being directed by a funnel 37 into an overflow trough 38 transversely overlying the topmost heating plate.

Coming now to that feature wherein the novelty of the present invention mainly resides. M designates as an entirety a mat which is superposed on the top surface of each heating plate which forms part of the trackway or path of the material in process and includes a finely divided body of catalyzing material, such as any of the several materials hereinabove specified. Within the broad aspects of the invention, this mat may embody any perforated or reticulated holder or container of a thin flat form, filled 90 with a body of the catalyzing material. I have herein shown one practical form which this mat may take, the same comprising a finely perforated lower plate or screen 39 having upturned flanges 40, and a similar finely 95 perforated top plate or screen 41 formed with downturned flanges 42 interfitting and bolted to the flanges of the bottom plate. In the space between the plates 39 and 41 is contained a filling 43 of the finely divided catalyzing agent. The mat thus formed rests directly on the top surface of the heating plate, it is of less cross-sectional area than the cross-sectional area of the conduit so as not to interfere with the upward 100 flow of the distilled vapors, and it is preferably retained in place by bolts 44 connecting the side flanges 40 to the upwardly turned edges or flanges 15' of the heating plate.

In the operation of the still, the material in process overflows from the trough 38 onto the top of the topmost mat, and from each of the inner series of headers 17 it overflows onto and through the next underlying mat. In its downward flow over each mat equipped heating plate, the material in process permeates the catalyzing material throughout practically the entire length of the mat, coming into very intimate contact with the catalyzing material while being heated, and being so modified by the latter as to greatly increase its cracking capacity.

While I have herein shown and described a specific embodiment of the principle of my invention, it will be understood that the latter is not limited to the specific apparatus herein disclosed, but may be structurally modified and employed in other specific structures of boiler or still without depart-

ing from the principle of the invention or sacrificing any of the advantages thereof. Hence, I reserve all such modifications and variations as fall within the spirit and pur-
5 view of the appended claims.

I claim—

1. A still for hydrocarbon distillation systems comprising, in combination, a heating conduit for the gravity flow of the material to be distilled, said conduit being of sufficient cross-sectional area to permit the generation of vapor therein and its outflow therefrom in a direction counterflow to the material undergoing distillation, a container screen of less cross-sectional area than the cross-sectional area of said conduit resting on the bottom of the latter in the path of flow of said material, and a body of catalyzing material in said screen.
- 10 2. A still for hydrocarbon distillation systems comprising, in combination, inter-nested hollow heating plates forming be-tween them a zigzag conduit for the grav-ity flow of the material to be distilled, con-tainer screens mounted on the heating plates which form the bottom wall of said conduit, and a body of catalyzing material within each screen.
- 15 3. A still for hydrocarbon distillation sys-tems comprising, in combination, inter-nested hollow heating plates forming be-tween them a zigzag conduit for the gravity flow of the material to be distilled, con-tainer screens of substantially the same sur-
20 face area as said heating plates covering the

heating plates which form the bottom wall of said conduit, and a finely divided body of solid catalyzing material filling each of said screens.

4. A still for hydrocarbon distillation sys-tems comprising, in combination, inter-nested hollow heating plates forming be-tween them a zigzag conduit for the grav-ity flow of the material to be distilled, and a mat overlying and substantially covering one or more of the heating plates which form the bottom wall of said conduit, said mat comprising upper and lower finely per-forated plates united at their margins, and a finely divided body of solid catalyzing material between and confined by said plates.

5. A still for hydrocarbon distillation sys-tems comprising, in combination, inter-nested hollow heating plates forming be-tween them a zigzag conduit for the grav-ity flow of the material to be distilled, each of said heating plates having vertical side flanges, and a mat overlying and substan-tially covering one or more of said heating plates which form the bottom wall of said conduit, said mat comprising upper and lower finely perforated plates united at their margins and having vertical flanges secured to the flanges of said heating plates, and a finely divided body of solid catalyz-ing material between and confined by said plates.

FRANCIS M. HESS.
